Whole No. 1421.   Samuel R. Hawley, of New York, N.Y.
Letters Patent No. 56, dated May 28, 1861.

The schedule referred to in these Letters Patent and making part of the same,

is all whom it may concern:

Be it known that I, S. R. Hawley, of the City, County

Dec. 14 21

and State of New York, have invented or produced a new and original Design for a Felt or Soft Hat, which I term the Star Spangled Hat, and I do hereby declare that the following is a full, clear and exact description of the same, reference being had to the accompanying drawings making a part of this specification, in which.

Figure 1. is a perspective view of a Hat constructed or formed according to my design.

Figure 2. a reduced plan or top view of ditto.

Figure 3. an inverted plan or top view of ditto.

Similar letters of reference indicate corresponding parts in the several Figures.

This invention or design consists in having embossed or otherwise produced on the crown A. of the hat, thirteen (13) stars, twelve of which a, are arranged in the form of a circle, and one b being at the centre, of the circle, the central one being larger than the others, as shown clearly in Figures 1 and 2.

On the brim B. of the hat near its edge there are formed thirty four (34) stars c, which are about equal in dimensions to the stars a, on the crown. The stars c, extend entirely around the brim B. as shown in all the Figures.

The thirteen stars on the crown A. are emblematical of the thirteen original states of the American Union, while the thirty four stars on the brim are emblematical of the thirty four states which at present comprise the American Union.

The shape or form of the hat may be the same as that generally given the felt or soft hats; to wit, the crown being low and the brim wide as shown in Figure 1. and any proper band d, may be used on the crown, and also any proper device on the tip D. within the crown. Neither the band C. nor the tip D. it will be understood from any part of the design.

The hat with the stars on the crown and brim as described forms a truly national design suggestive of the title which I have given it. "The Star Spangled Hat."

Having thus described my invention what I claim as new and desire to secure by Letters Patent is,

The general configuration of the stars a. b. c, respectively.

3

on the crown A, and brim B, as shown to form a new and original design for a hat.
